UNITED STATES PATENT OFFICE.

JOHN MAURICE BROCK, OF BROOKLYN, NEW YORK.

ATTACHING DEVICE FOR MINERS' CAP-LAMPS.

1,289,631.

Specification of Letters Patent. Patented Dec. 31, 1918.

Application filed June 19, 1918. Serial No. 240,870.

To all whom it may concern:

Be it known that I, JOHN M. BROCK, a citizen of the United States, residing at Brooklyn, in the county of Kings and State 5 of New York, have invented certain new and useful Improvements in Attaching Devices for Miners' Cap-Lamps; and I do hereby declare the following to be a full, clear, and exact description of the invention, 10 such as will enable others skilled in the art to which it appertains to make and use the same.

This invention relates to attaching devices for miners' cap lamps.

15 The usual miner's cap lamp is provided with a hook which may be hooked through a suitably located orifice in a supporting plate or shield secured to the front of the miner's cap, the lower part of the lamp body, 20 being held steady and connected to the supporting plate by appropriate means of some description. Heretofore, such means have commonly taken the form of a clamping brace or jaw device permanently secured to 25 the rear of the lamp and adapted to engage the supporting plate; or else a spring clip device has been permanently secured to the supporting plate in position to receive and hold a lamp body. Both these arrangements 30 are open to objection. Permanent attachment of the clamping or gripping means to the lamp is often undesirable because, among other reasons, it complicates the lamp construction. On the other hand, permanent 35 attachment of a spring clip device to the supporting shield has the disadvantage, among others, of restricting the use of the shield with its attached clip to lamps whose vertical height happens to be suited to the 40 particular location of the clip on the shield. Again, replacement or repair of either of these devices, when required, is necessarily difficult by reason of the permanent attachment of the device either to the lamp or the 45 shield, and is usually impracticable.

A principal object of the present invention is to provide a simple and thoroughly practical construction wherein the objections above mentioned are overcome, and 50 wherein certain new and desirable results are attained.

Another object of the invention is to provide a suitable lamp clip which is adapted also for use independently of a supporting 55 plate or shield of the character above mentioned.

Other and further objects of the invention will appear as the description proceeds.

Generally described, the invention in its most desirable form, comprises a device 60 wherein lamp-engaging means and shield-gripping means are embodied in a combined construction which is detachable from and adjustable with respect to both the shield and the lamp. To this end, the best embodiment of the invention comprises resilient clip means adapted to releasably engage and hold a lamp body, and resilient gripping or clamp means adapted and arranged to adjustably engage a supporting member, and 65 more particularly to engage an opposite pair of edges of a shield of the character referred to, in such manner as to hold the lamp with its supporting clip in firm connection with the shield, while at the same 70 time the position of said gripping means on the shield can be varied as may be necessary or desirable to properly accommodate lamps of different sizes and types of construction.

80 A full understanding of the invention can best be given by describing in detail a typical embodiment thereof, such as that illustrated in the accompanying drawings, 85 wherein—

Figure 1 is a view in side elevation showing an attaching device constructed in accordance with the invention, in combination with a cap shield or supporting plate, the assemblage constituting complete lamp attaching means.

Fig. 2 is a horizontal section on the line 2—2 of Fig. 1;

Fig. 3 is a perspective view of the detachable combined spring clip and clamping device, on a somewhat larger scale; and

Fig. 4 represents a pattern, on a still larger scale, showing how the combined device can be formed from a single piece of sheet metal.

100 Referring to the drawings, 10 represents a miner's cap to which is secured a holding plate or shield comprising the intermediate upright portion 11 at the front of the cap, the upper portion 12 being bent rearwardly and secured to the top of the cap as by rivet means 13, and the portion 14 being bent forwardly and downwardly over the cap vizor 15 and secured thereto as by rivet means 16. In the particular form of shield here illustrated, the shield is constructed of thin sheet metal 17, such as tin, and a reinforcing and

insulating layer of fiber 18, the lateral edges of the sheet metal piece being crimped over the fiber layer at 19 to hold the latter in place. The bend at the junction of the portions 11 and 12 projects forwardly somewhat in the form of a hollow bead 20, which is vertically slotted at 21; and the upper portion 12 of the shield is provided with a perforation at 22. The free end 23 of a hook, with which a miner's acetylene lamp 24 of well-known construction is provided, may be inserted through aperture 22; while the shank 25 of said hook can enter the vertical slot 21. The construction thus far described is well known in the art.

In accordance with the present invention, means are provided for adjustably engaging and holding the lower part of the lamp, in this instance the carbide container 26, structurally combined with means for adjustably clamping or gripping the vertical portion 11 of the lamp support or shield. The combined construction most desirably takes the form shown in the drawings and most clearly illustrated in Fig. 3. In this instance the combined device is formed from a single piece of sheet metal, suitably tempered to provide the necessary resiliency, and comprises a substantially semi-circular forwardly extending resilient lamp-engaging clip having arms 27 adapted to yieldably embrace the carbide container, the ends 28 being bent outward slightly in order to permit said carbide container to enter readily between the arms; in combination with rearwardly extending spring jaws 29, which are formed at 30 to firmly engage and grip the vertical edges of portion 11 of the shield. Said jaws 29 are here shown provided with apertures 29^a adjacent their upper edges, for a purpose hereinafter explained. The ends 31 of said jaws are bent outwardly, as shown, to facilitate entry of the shield edges between the jaws and to provide finger holds whereby the jaws may be sprung apart slightly when it is desired to remove the clip from the shield or to facilitate adjustment of the clip device vertically to different positions on the shield. The proportioning and arrangement of the parts are such that when the lamp body or carbide container 26 is given a sufficiently strong forward pull, the arms 27 will yield to permit removal of the lamp; while at the same time the spring jaws 29 will not be affected. Most desirably the shape and arrangement of the spring jaws are such as to strongly resist detachment of the device from the shield except by outward pressure on either one or both of the divergent ends 31.

The particular form of the combined lamp-engaging and shield-gripping device here shown has special advantages for the purposes in view. Thus, for example, the bending of the clip arms 27 and jaws 29 op-

ositely in parallel planes from a common plane or line at 32, which is perpendicular to said parallel planes, provides a comparatively long vertical bearing of the device against the lamp body 26, thereby contributing materially to the solidity with which the lamp is held in place by the attaching structure as a whole. This portion 32 of the sheet metal which is common to both pairs of resilient arms and unites them, also has the effect of somewhat increasing the resistance which the arms of each clip offer to being spread apart, the clips being thus stiffened by virtually increasing their width at their line of union. In the integral construction illustrated, where the clips are in offset relation, the effective gripping power and resiliency of both clips is thus interdependent to a certain extent and is greater than in the case of separate clips or clips secured back to back. Again, springing apart the arms of one clip tends to close the arms of the other clip slightly; so that in actual use, when both clips are actively functioning as resilient clamps, the gripping effect of each is increased by the action of the other. In other words, flexing the arms of one clip transmits flexing stresses to the other pair. It is evident, however, that these parts of the device could be separately formed and united in any appropriate manner to produce a detachable clip device of the character described, instead of being formed integral, though the assembled construction would be less advantageous. Other changes in the details of construction here shown and described for purposes of a concrete example, may also evidently be made without departing from the spirit of the invention.

It is to be noted that the described clip device can also be used without a cap shield or supporting plate, for attaching a lamp directly to a cap, or hat, or in cases where the lamp is to be carried suspended from the buttonhole in the coat lapel. Under these circumstances, the holes 29^a in the arms 29 constitute provision whereby the clip device can be fastened to the cap, hat, or lapel, by means of rivets or staples, the snaps or gripping pieces 30, 31, most desirably having been first cut off. Another desirable feature of the clip device is that it will hold a lamp which has no hook, thus enabling the lamp to be swung around at any angle and to direct the light laterally to right or left while the wearer is looking straight ahead. Drivers and car couplers in mines find this of considerable practical importance.

What I claim is:

1. Attaching means for miners' cap lamps comprising the combination with a supporting plate adapted to be fastened to a miner's cap, of adjustable clamping means arranged to grip opposite edges of said plate, and

resilient clip means connected to said clamping means and adapted to engage and releasably hold a lamp body.

2. Attaching means for miners' cap lamps comprising the combination with a supporting plate adapted to be fastened to a miner's cap, of a detachable clip device adapted and arranged to releasably engage and hold a lamp body and also to releasably grip the edges of said plate.

3. Detachable clip means for miners' lamps comprising oppositely extending pairs of resilient arms secured together, one pair constituting a substantially semi-circular spring clip adapted to engage and releasably hold the body of a miner's lamp, and the other pair constituting spring jaws adapted to grip opposite edges of a supporting plate or shield, substantially as described.

4. Detachable clip means for miners' lamps comprising oppositely extending pairs of resilient arms formed from a single piece of sheet metal in such manner that flexure of one pair of arms transmits flexing stresses to the other pair, one pair constituting a spring clip to releasably hold a miner's lamp, and the other pair constituting means for attachment to a support.

5. Detachable clip means for miners' lamps comprising oppositely extending pairs of resilient arms formed from a single piece of sheet metal in such manner that flexure

of one pair of arms transmits flexing stresses to the other pair, one pair constituting a spring clip to releasably hold a miner's lamp, and the other pair terminating in gripping jaws.

6. Detachable clip means for miners' lamps comprising oppositely extending pairs of resilient arms formed from a single piece of sheet metal, one pair constituting a spring clip to releasably hold a miner's lamp, and the other pair terminating in gripping jaws and having additional provision to aid in attaching the clip means to a support.

7. Detachable clip means for miners' lamps comprising oppositely extending pairs of resilient arms formed from a single piece of sheet metal, one pair constituting a spring clip to releasably hold a miner's lamp, and the other pair terminating in gripping jaws and being apertured to accommodate attaching means.

8. Detachable clip means comprising two pairs of resilient arms united along a common line and bending directly and oppositely therefrom in different parallel planes.

9. Detachable clip means comprising two pairs of resilient arms formed from a single piece of sheet metal and bending in opposite directions directly from a common line of union and in offset relation.

In testimony whereof I hereunto affix my signature.

JOHN MAURICE BROCK.
